DESIGN FOR A WISHING BOWL

Evangeline Day, New York, N. Y.

Application June 13, 1936, Serial No. 63,271

Term of patent 7 years

To all whom it may concern:

Be it known that I, Evangeline Day, a citizen of the United States of America, residing at New York city, in the county of New York, Borough of Manhattan, and State of New York, have invented a new, original, and ornamental Design for a Wishing Bowl, of which the following is a specification, reference being had to the accompanying drawing, forming a part thereof:

The characteristic feature of the design resides in the arrangement of the symbols and indicating signs as shown.

I claim:

The ornamental design for a wishing bowl, as shown and described.

EVANGELINE DAY.
